UNITED STATES PATENT OFFICE

BERNARD SASSEN, OF CINCINNATI, OHIO, ASSIGNOR TO THE CINCINNATI MILLING MACHINE COMPANY, OF CINCINNATI, OHIO, A CORPORATION OF OHIO

SELF-REGULATING HYDRAULIC SYSTEM

Application filed April 8, 1930. Serial No. 442,565.

This invention seeks to effect an improvement in the common or more usual type of hydraulic transmission which, it will be remembered, conventionally employs a variable-delivery pump arranged to propel a motor by supplying, through a regulated forward-pressure line, a predetermined flow. The out-take from the motor is, in this conventional system, free or substantially so. Consequently this system is unadapted for any usage which requires the motor to act as a brake for regulating the rate caused by a negative work-resistance; as in cutting with the feed in a milling machine.

It is now proposed to overcome this objection by means for automatically maintaining a regulated back-pressure in the out-take line from the motor; returning the out-flow from this means at a low-pressure directly to the reservoir, if desired, but preferably at a low constant pressure to the in-take of the variable-delivery pump.

While the present system, in each of its embodiments, maintains the system full of oil at all times, regardless of the in-flux and out-flux necessitated if a motor of the differential type be used, it also lends itself to a compensation for leakage which otherwise would affect the feed rate, and how this may be accomplished will be explained later.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:—

Figure 1 diagrammatically represents an embodiment of the more elementary principle underlying this invention. Fig. 2 diagrammatically discloses an improved form of this invention; while, Fig. 3 diagrammatically sets forth how this invention may be embodied to ensure a feed rate unaffected by

any incidental leakage and, additionally, to render available a high pressure take-off line for service in actuating any device or instrumentality auxiliary to the main machine.

It is to be understood that this system finds its practical application in various types of machine-tools; but more especially in "milling-machines" and these diagrams are to be interpreted accordingly. Thus, T is the machine-element propelled hydraulically by the motor M⁴, and V¹V² represents the valve-means for appropriately arresting or directing the flow to and from the motor to obtain all such motions of the machine-element as have heretofore been automatically produced by mechanical means; such, for example, as a rapid-traverse during a non-cutting shift, or a feed during a tooling movement; singly or combined in the various cycles (involving either forward or return movements or both) conventional with machine-tool practise. Inasmuch as the dogs and trips already developed in purely mechanical machines are readily available to engineers, and likewise as to the organization of the valve-means, it is deemed unnecessary to describe such in detail; for to do so would tend to obscure rather than clarify a disclosure of the salient characteristics. For the benefit of those not versed in the art, reference will, however, be made to the British Patent No. 297,104 which very fully shows valve and trip means such as is herein indicated diagrammatically by V¹V², as well as other details of a complete machine.

It will suffice to say, before dwelling on the distinguishing features of this invention, that the work-table T will be connected to the motor by some sort of mechanical drive indicated by the arm 15 and piston-rod 14 which enters the cylinder 12 and is attached to the piston 13. The type of the motor M⁴ is not of the essence of this invention, and hence is herein shown in the form most practicable and inexpensive for most installations; to wit, as a differential piston-and-cylinder motor.

Its ports are indicated by x and y; the one being the inlet and the other the outlet ac-

cording to the direction of flow which, in turn, is determined by the setting of the valve-means V^1V^2 . If the "stop" valve V^2 be open, communication between the ports 10— a and 11— b is established, and the motor may be propelled; rapidly if the constant displacement pump C. D. be connected through the selector valve V^1 ; or at a feed-rate if the variable displacement pump V. D. 15 be connected. The direction of actuation, in either case, will likewise be determined by the setting of the selector valve V^1 ; to wit, as to whether terminal P^3 is communicated with terminal a^1a^2 or b^1 and H^2 with b^1 or 20 a^1a^2 for a feed-stroke; or terminal 3 with a^1a^2 or b^1 , and 5 with b^1 or a^1a^2 for a quick-traverse stroke.

The position of the valve V' shown diagrammatically in the drawings indicates its 25 position when the table T is feeding to the right. If the valve is oscillated, terminals 3— b^1 and 5— a^2 will be connected and a traverse rate ensues; if the valve is next shifted axially, terminals P^3 — b^1 and H^2 — a^1 30 will be connected which reverses the feed connections and the motor is driven to the left at a feed rate, etc. Inasmuch as the valve means herein illustrated are representative of a conventional selector valve of the 35 type illustrated in the above mentioned British patent, further description thereof, in the interests of clarity, has been thought to be unnecessary.

In each of the diagrams; the motor feed-stroke out-take line (characterized by a relatively high back-pressure) is indicated by H and may be said to embrace the portion starting from the valve means V^1V^2 at H^2 and ending at H^1 where the automatic choke is 40 located. This choke takes form, preferably, as a differential valve indicated generally by D which, in turn, admits of modification. In its more elementary form (represented by Fig. 1) it maintains the back-pressure at a 45 constant high value by reason of the conduit S^1 which connects the low constant-pressure line L with the larger chamber of the valve; the valves being represented by $Hd^1=Ld^2$ where H and L are the potentials and d^1 and 50 d^2 the respective areas of the differential valve. In place of the connection S^1 , a spring S may be employed as shown by Figs. 2 and 3, or conversely.

In the case of application to a milling machine, the conditions of usage generally are best met by a further refinement; to wit, the additional influence of the forward-pressure which, as shown by Figs. 2 and 3, is introduced by the connection P^4 from the forward line P to the chamber P^2 of the differential valve. In this case, if S_1 be the unit pressure of the spring, and the idling pressure in the lines be represented by H_1 , then

$$S_1 = H_1 (R_1 + 1)$$

where R_1 is the ratio of the differential valve. If the work-resistance be negative, then will the high-pressure back-line prevent over-run of the motor, and the forward-pressure will be relatively low. If the work-resistances be positive, then will the motor be propelled by the forward-pressure which then will be greater than the back-pressure depending, in amount, on the extent of work-resistance.

This forward-pressure is derived from the V. D. pump which delivers oil at a selectable volumetric rate through the outlet port P^1 into the line P which at P^2 enters the valve-means and is directed thereby as has been explained. The V. D. pump may draw its supply directly from the reservoir R but, as a matter of simplicity in piping and for other reasons, it preferably derives its supply from the oil exhausted under low-pressure by the differential valve D. This will exceed the needs of the V. D. pump when the exhaust comes from the large end of the differential motor, and will be insufficient when it comes from the piston-rod end. But if a non-differential motor be used, then it will be equal in each direction of actuation.

Of course, if no rapid traverse be required for the mechanism, then the C. D. pump and its circuit may be omitted, and the V. D. pump may draw all or some of its supply directly from the reservoir; but it is desirable to arrange for a moderate head, at least, at the inlet port 7 of the V. D. pump because they are usually made without springs for returning the plunger and hence are not designed to operate under a negative inlet head.

Hence, in any event, it is more satisfactory to substitute a small pump purely for make-up purposes if the larger capacity C. D. pump is not primarily needed for quick-traverse operations and incidentally used for make-up purposes. Such a pump, whether large or small, draws its supply directly from the reservoir R and discharges into the low-pressure line L which usually has a safety relief X set for a pressure too high to yield except in an emergency. The main flow from the constant displacement pump ultimately discharges back to the reservoir through a free line F either after first entering the motor or through a connection from terminals 3 to 5 provided by the valve-means V^1V^2 . But, to ensure a low constant-pressure available for the inlet of the V. D. pump, a low fixed resistance valve 4 is arranged to choke the discharge of the C. D. pump. Between that resistance 4 and the C. D. pump, as at 2, a communication is established with the inlet port 7 of the V. D. pump and this communication extends, as indicated by the line 8—9 to the outlet of the differential valve D.

Now, by way of a further refinement of this invention, to compensate for variations in the feed-rate attributable to such leakage

as occurs between the forward-pressure and the reservoir, it is proposed to arrange for a high-pressure bleed into the forward-pressure line P. How this may be done is disclosed by Fig. 3; in which B represents a small-displacement high-pressure booster-pump which draws its oil from any available source which, as a matter of convenience, may be at some point m in communication with the low-pressure line so as to have a positive pressure on the pump inlet for the reason previously explained.

This booster-pump discharges at m^1 into the line M which at m^4 connects with an adjustable orifice O which bleeds into the forward-pressure line P. If the pressure in the line M be constant in ratio to the forward-pressure in line P for all variations in the latter, and if the orifice O be initially adjusted to the leakage factor of the particular machine, then will the compensation remain exact for all variations in work-resistance.

This constant ratio is obtained by an automatic drainage of excess fluid by the operation of a differential valve C which, for the purpose of this disclosure, is illustrated as being proportioned in a 2:1 ratio. Its tapered stem, which governs the drainage (through the line from the point m^2 to the inlet c^1 and variable outlet c^2), is of one half the area of the head which is subjected to the pressure of forward-pressure line P; the communication being through the inlet c^3 and the line to the point P¹. The pressure in the line M will, accordingly always be twice the forward-pressure in the line P, and if the orifice O be once adjusted to equal the aggregate leakage orifices from the outlet of the V. D. pump to the reservoir, then a perfect compensation will be ensured for this type of leakage. This will suffice for most cases.

So also, for the operation of any auxiliary mechanism, a high-pressure take-off line N may be provided.

If greater refinement in compensation be required, (for leakage between forward-pressure in line P and the intake of the V. D. pump) this invention proposes the use of another differential valve E. Since this type of leakage has also a retarding effect on the feed-rate, and hence must be compensated for by a bleed-in, and since it will in amount vary in direct proportion to the differentials (between the forward and back-pressures) created by the variations in the work resistance; the valve E should be capable of ascertaining such differentials and operate in accordance therewith. The back-pressure on the V. D. pump is, in this system, constant and hence can be represented in the valve by a spring of equal unit pressure value and arranged to act in opposition to the component of the forward-pressure. As the area of the plunger head subjected to the forward-pressure is double the area of the stem which

(through port e^1) is subjected to that of the auxiliary bleeder-line W, the latter will be maintained under a pressure of $2P - S''$. And, by the line W, the fluid will be available for bleeding-in at a pressure greater than the forward-pressure by an amount equal to the differential. So to compensate for the leakage between P and L, it is only necessary to interpose in the line W an adjustable choke G for setting the rate of bleed into the forward line P according to the leakage characteristic of the particular machine.

By following the principles disclosed, exact compensation for local leakage may be had between any two stations in an hydraulic system by utilizing additional valves of this type arranged in series with the above described valves.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be, comprehended within the meaning and range of equivalency of the following claims.

Having thus revealed this invention, I claim as new and desire to secure the following combinations and elements, or equivalents thereof, by Letters Patent of United States:—

1. An hydraulic system combining a motor; a variable delivery pump arranged to receive its fluid at the intake side thereof at a relatively low pressure and to deliver same to said motor at a predetermined rate; and means maintaining the discharge from said motor under a relatively high pressure comprising a valve mechanism, having a variable orifice, adapted to respond to the combined influence of the motor discharge and pump intake pressures.

2. An hydraulic system combining a motor; a variable delivery pump arranged to receive its fluid at a relatively low pressure and to deliver same to said motor at a predetermined rate; and means maintaining the discharge from said motor under a relatively high pressure comprising a valve mechanism, having a variable orifice, adapted to respond to the combined influence of the pressures ahead of and behind the valve.

3. An hydraulic system combining a low-pressure pump; a variable-delivery pump; a conduit therebetween; a motor; a motor intake line connectible with said variable delivery pump; an out-take line from said motor to said conduit; and a high-pressure relief-valve in said out-take line for maintaining said motor under a relatively high

- back-pressure but reducing to a low-pressure the discharge into said conduit.
4. An hydraulic system combining a variable-delivery pump; a constant-delivery pump; a discharge-line from the latter pump; a relatively-low resistance in said line; a variable-delivery pump having its intake connected to said discharge-line between said resistance and said constant-delivery pump;
- 10 5. An hydraulic system combining a variable-delivery pump; a constant-delivery pump; a discharge-line from the latter pump; a relatively-low resistance in said line; a variable-delivery pump having its intake connected to said discharge-line between said resistance and said constant-delivery pump; a motor arranged to receive the liquid from said variable-delivery pump; an out-take line from said motor; and an automatic relief valve for maintaining a relatively-high back-pressure in said out-take line.
- 15 6. An oil-transmission system combining a motor; an unrestricted return-conduit; a restricted out-take line; an automatic means responsive to variations in the pressure of the controlled fluid for controlling the degree of said restriction; a source of low-pressure oil; a variable-delivery pump; valve-means for connecting said source and return-conduit with said motor to propel it rapidly and alternatively available to connect said motor with said variable-delivery pump and said restricted out-take line.
- 20 7. An hydraulic system combining a motor; a variable-delivery pump; an in-take line from said pump to said motor; an out-take line from said motor; and a differential plunger and an escapement valve operated thereby for regulating the out-flow in said out-take line, said differential plunger connected to said in-take line.
- 25 8. An hydraulic system combining a motor; an in-take line leading thereto; an out-take line leading therefrom; a source of fluid supply connected with the intake line; and means in said out-take line for automatically diminishing the back-pressure therein in accordance with increases of the forward-pressure in the in-take line.
- 30 9. An hydraulic system combining a motor; in-take and out-take lines therefor; and a differential valve, having a variable orifice, in the out-take line and adapted to respond to the combined pressures in both lines for varying the effectiveness of said orifice thereby; to regulate the back-pressure in the out-take line.
- 35 10. An hydraulic system combining a motor; a variable-delivery pump; an in-take line from said pump to said motor; an out-take line from said motor; and a differential valve in said out-take line and provided with a variable orifice for regulating the out-flow, said differential valve being connected to said in-take and out-take lines and proportioned to be more sensitive to variations in the forward than in the back-pressure in effecting variations in the resistance to flow offered by the valve.
- 40 11. An hydraulic system combining a motor; an intake-line leading thereto; an out-take line leading therefrom; means in said out-take line for automatically diminishing the back-pressure therein in a predetermined ratio to increases in the forward-pressure in the intake-line; selective means for supplying said in-take line with oil at a predetermined volumetric rate; and valve means for connecting said in-take line to drive said motor in either direction.
- 45 12. An hydraulic system combining a motor; in-take and out-take lines therefor; and a differential valve in the out-take line provided with a variable orifice and having respective areas subjected to the pressures of both lines for regulating the effectiveness of the valve orifice thereby to regulate the back-pressure in the out-take line, the area subjected to the forward pressure being relatively large.
- 50 13. An hydraulic system combining a motor; a large-volume low-pressure pump; a variable-delivery pump adapted to receive fluid therefrom; a low-pressure escapement between said pumps for maintaining the oil received by said second pump at a low constant-pressure; valve means adapted to connect said motor with said low-pressure pump, or to receive the out-put from said variable-delivery pump; an out-take line from said motor; and a differential valve in said line having a variable orifice capable of variation by the combined influence of the in-take and out-take pressures on said motor; for automatically regulating the flow in said line.
- 55 14. An oil-transmission system combining a motor; a free-return conduit; a restricted out-take line; a differential valve automatically responsive to variations in the pressure of the controlled fluid controlling the degree of said restriction; a source of low-pressure oil; a variable-delivery pump; valve-means for connecting said source and said free-return conduit with said motor to propel it rapidly, and alternatively available to connect said motor with said variable-delivery pump and said automatically restricted out-take line.
- 60 15. An hydraulic system combining motor; a constant displacement pump; an output and free-return line; valve means selectively operable for connecting said motor,

- 5 pump, and lines for rapid-propulsion; a variable-delivery pump; a motor in-take line therefrom; a motor out-take line; means maintaining a relatively high back-pressure in said out-take line and permitting discharge at a relatively low-pressure into said variable-delivery pump; a make-up connection from the aforesaid out-put line to the inlet of said variable-delivery pump; and a resistance beyond said connection in said out-put line for maintaining a relatively low constant-pressure in said connection, the first-mentioned valve-means being alternatively operable to connect said motor with said variable-delivery pump through said in-take and out-take lines.
- 10 16. An hydraulic system combining a variable-delivery pump; a make-up pump having an out-put line; means for maintaining in a portion of said out-put line a relatively low constant-pressure; a connection from said portion to the variable-delivery pump; a motor; an in-take line thereto from said variable-delivery pump; an out-take line from said motor to said variable-delivery pump; and intervening means in said out-take line for maintaining said motor under a relatively high back-pressure.
- 15 17. An hydraulic system combining a motor; a constant displacement pump; an out-put and free-return line; valve means selectively operable for connecting said motor, pump, and lines for rapid-propulsion; a variable-delivery pump; a motor in-take line therefrom; a motor out-take line; differential valve means responsive to variations in pressure in portions of the system for maintaining a relatively high back-pressure in said out-take line and permitting discharge at a relatively low-pressure into said variable-delivery pump; a make-up connection from the aforesaid out-put line to the inlet of said variable-delivery pump; and a resistance beyond said connection in said out-put line for maintaining a relatively low constant-pressure in said connection, the first-mentioned valve-means being alternatively operable to connect said motor with said variable-delivery pump through said in-take and out-take lines.
- 20 18. An hydraulic system combining a variable-delivery pump; a make-up pump having an out-put line; means for maintaining in a portion of said out-put line a relatively low constant-pressure; a connection from said portion to the variable-delivery pump; a motor; an in-take line thereto from said variable-delivery pump; an out-take line from said motor to said variable-delivery pump; and a differential valve in said out-take line, responsive to pressure variations in the controlled fluid, for maintaining said motor under a relatively high back-pressure.
- 25 19. An hydraulic system combining a motor; a variable-delivery pump; an in-take line from said pump to said motor; an out-take line from said motor; and a differential valve having an automatically variable orifice for regulating the out-flow in said out-take line, said differential valve connected to said in-take line; and automatic means for injecting fluid into the in-take line to compensate for leakage.
- 30 20. An hydraulic system combining a motor; an in-take line leading thereto; an out-take line leading therefrom; a source of fluid supply connected with the in-take line; and means in said out-take line for automatically diminishing the back-pressure therein in accordance with increases of the forward-pressure in the in-take line; and automatic means for injecting fluid into the in-take line to compensate for leakage.
- 35 21. An hydraulic system combining a motor; in-take and out-take lines therefor; and a differential valve in the out-take line acting under the combined pressures in both lines to regulate the flow and thereby control the back-pressure in the out-take line; and automatic means for injecting fluid into the in-take line to compensate for leakage.
- 40 22. An hydraulic system combining a motor; a variable-delivery pump; an in-take line from said pump to said motor; an out-take line from said motor; and a differential valve provided with a variable opening in said out-take line for regulating the out-flow, said differential valve being connected to said in-take line and proportioned to be more sensitive to variations in the forward than in the back-pressure in varying the effectiveness of the valve opening; and automatic means for injecting fluid into the in-take line to compensate for leakage.
- 45 23. An hydraulic system combining a motor; a large-volume low-pressure pump; a variable-delivery pump adapted to receive fluid therefrom; a low-pressure escapement between said pumps for maintaining the oil received by said second pump at a low constant-pressure; valve means adapted to connect said motor with said low-pressure pump, or to receive the out-put from said variable-delivery pump; a motor intake line; an out-take line from said motor; a differential valve in said out-take line, said valve being connected with said in-take and out-take lines and provided with an orifice capable of variation by and in accordance with variations in the combined influence of the in-take and out-take pressures on said motor; and automatic means for injecting fluid into the in-take line to compensate for leakage.
- 50 24. An hydraulic system combining a motor; a constant displacement pump; an out-put and free-return line; valve means selectively operable for connecting said motor, pump, and lines for rapid-propulsion; a variable-delivery pump; a motor in-take line therefrom; a motor out-take line; means

- maintaining a relatively high back-pressure in said out-take line and permitting discharge at a relatively low-pressure into said variable-delivery pump; a make-up connection from the aforesaid out-put line to the inlet of said variable-delivery pump; and a resistance beyond said connection in said out-put line for maintaining a relatively low constant-pressure in said connection, the first-mentioned 5 valve-means being alternatively operable to connect said motor with said variable-delivery pump through said in-take and out-take lines; and automatic means for injecting fluid into the in-take line to compensate 10 for leakage.
25. An hydraulic system combining a variable-delivery pump; a make-up pump having an out-put line; means for maintaining in a portion of said out-put line a relatively low 20 constant-pressure; a connection from said portion to the variable-delivery pump; a motor; an in-take line thereto from said variable-delivery pump; an out-take line from said motor to said variable-delivery pump; and 25 intervening means in said out-take line for maintaining said motor under a relatively high back-pressure; and automatic means for injecting fluid into the in-take line to compensate for leakage.
30. 26. An hydraulic system combining a variable-delivery pump; a make-up pump having an out-put line; means for maintaining in a portion of said out-put line a relatively low constant-pressure; a connection from said 35 portion to the variable-delivery pump; a motor; an in-take line thereto from said variable-delivery pump; an out-take line from said motor to said variable delivery pump; and a differential valve, provided with a vari- 40 able orifice, in said out-take line for maintaining said motor under a relatively high back-pressure; said valve responding to variations in pressure of the controlled fluid to regulate the effectiveness of the valve orifice; 45 and automatic means for injecting fluid into the in-take line to compensate for leakage.

In witness whereof, I have hereunto subscribed my name.
